UNITED STATES PATENT OFFICE.

JOHN HOLLAND, OF LIMERICK, MAINE.

BED-BLANKET.

SPECIFICATION forming part of Letters Patent No. 271,461, dated January 30, 1883.

Application filed December 30, 1882. (No model.)

To all whom it may concern:

Be it known that I, JOHN HOLLAND, of Limerick, in the county of York and State of Maine, have invented certain Improvements 5 in Bed-Blankets, of which the following is a full, clear, and exact description, reference being had to the accompanying drawings, making part of this specification, in which—

Figure 1 represents a double bed-blanket of 10 my improved manufacture spread open. Fig. 2 represents a single bed-blanket with my improvements applied thereto.

In Fig. 1 of said drawings, A represents a bed-blanket of such length that when folded 15 on the dotted line xx it will form a double blanket. The two upper or top edges of the folded blanket are each covered with a binding, a , and located a short distance therefrom is an embroidered border, b , of flowers extending transversely therewith—being produced thereon preferably by an embroidering-machine—the needle of which carries the silk of the required color through from one side of the 20 blanket to the other. The embroidered border 25 may, however, be produced by hand-sewing; or the border may be simply stamped on one

or both sides. A braid may also be stitched on the surface or outside of the blanket over a pattern previously delineated thereon, and a border may be produced by stitching a pattern of any desired form previously cut from a strip of silk, velvet, woolen, or other suitable material.

The border may be composed of figures of flowers, vines, birds, animals, portraits of individuals, or other representations.

The blanket shown in Fig. 2, being single, requires but one border b near its top or upper edge.

I claim—

As a new article of manufacture, a single or double bed-blanket provided at or near its upper edge or edges with an ornamental design, constituting a border therefor, substantially as described.

Witness my hand this 19th day of December, 1882.

JOHN HOLLAND.

In presence of—

E. P. MERRITT,
A. C. THOMAS.
